UNITED STATES PATENT OFFICE

2,183,104

BOILER FEEDER

Cecil W. Preston and Daniel F. Ellis, Chicago, and James D. Jordan, Oak Park, Ill., assignors to General Household Utilities Company, Chicago, Ill., a corporation of Delaware

Application September 4, 1937, Serial No. 162,562

18 Claims. (Cl. 62—115)

The present invention relates in general to the delivery of fluid into a chamber or container under relatively high pressure from a source or reservoir at lower pressure, and the invention 5 has more particular reference to boiler feed apparatus, and while the invention is especially adapted for the delivery of liquid in the boiler of refrigerating apparatus of the character illustrated and described in the co-pending application 10 of William C. Grunow et al. for United States Letters Patent, Serial No. 144,346, filed May 24, 1937, the present invention is not restricted to use in conjunction with refrigerating apparatus, but may have general application in 15 connection with the delivery of fluid to a boiler or like relatively high pressure chamber of any apparatus.

An important object of the invention is to provide simplified means for feeding liquid into a 20 container, such as a boiler, from a supply source which is at a relatively lower pressure, the invention relating more particularly to the provision of simplified means having a minimum number of moving parts whereby the same does 25 not readily get out of order in service.

Another important object is to provide a boiler 30 feed device operable in conjunction with the condenser of a refrigerating system and a boiler providing vapor under pressure for the actuation 35 of jet pumps for causing circulation of a refrigerant in the refrigerating system in order to deliver liquid from the condenser into the boiler against the relatively high pressure maintained therein during the operation of the system.

Another important object is to utilize vapor 40 under pressure derived from the boiler itself for the operation of the boiler feed device; a further object being to utilize an actuating element containing an evaporable medium adapted to vaporize at a temperature slightly less than the vaporizing temperature of the medium delivered to the boiler in order to cause operation of the boiler feed device.

Another important object is to provide means 45 for utilizing differentials of pressure and temperature in the feeding device augmented by forces developed by a medium having a vaporizing temperature less than the boiler feed medium in order to utilize boiler pressure to aid in the 50 delivery of the boiler feed medium to the boiler.

Another important object is to accomplish the 55 delivery of a boiler feed medium in a boiler from a supply source at relatively lower pressure by providing a feeding device comprising a chamber having valved communication with the boiler

and with the supply source including expandible means subjected to temperature conditions within the chamber for actuating the valved connections to permit vapor at boiler pressure to enter the chamber at intervals in order to permit liquid previously delivered into the chamber from the source to flow by gravity into the boiler, while at the same time preventing vapor at boiler pressure from reaching the source of supply of the boiler feed medium; a further object being 10 to utilize any thermo-responsive element which may include an expandible diaphragm or bellows and may contain a medium having a vaporizing temperature less than that of the boiler feed medium; a still further object being to utilize 15 the mechanical movement of the bellows in order to control the valved connections.

Another important object is to provide a shield for the expandible element in order to control the transfer of heat thereto from the boiler feed 20 medium as the same enters the chamber in relatively cold condition from the source of supply; a further object is to utilize the heat shield as a guide for the expandible actuating element.

Another important object is to provide a boiler 25 feed device in which the temperature of the boiler feed medium is raised prior to delivery of the medium into the boiler.

Numerous other objects, advantages and inherent functions of the invention will become 30 apparent as the same is more fully understood from the following description which, taken in connection with the accompanying drawing, discloses preferred embodiments of the invention.

Referring to the drawing:

Fig. 1 is a diagrammatic showing of a refrigerating system of the character illustrated and described in the aforesaid application of William C. Grunow for United States Letters Patent, and containing boiler feeding means embodying the 40 present invention.

Fig. 2 is an enlarged sectional view of the feeding means shown in Fig. 1; and

Figs. 3 and 4 are sectional views of somewhat diagrammatic character and illustrating 45 modified arrangements of the feeding device in order to demonstrate the principle of the present invention.

To illustrate our invention we show on the drawing a feeding device 11 for delivering a fluid 50 into a container 13, such as a boiler, at relatively high pressure from a source of supply 15 at relatively lower pressure, and while the invention may have general application, particularly in feeding liquid to boilers, we have shown 55

the device 11 connected in a refrigerating system of the character illustrated in the application of William C. Grunow for United States Letters Patent, Serial No. 144,346, filed May 24, 1937, the 5 same comprising a refrigerating system adapted for operation on the compression-condensation-evaporation cycle, wherein a refrigerating medium, in gaseous condition, is compressed by the pumping means 17 and delivered to a condenser 19, and wherein the refrigerating medium is 10 cooled to liquefy the same at substantially compression pressure. The liquefied medium may then be delivered through suitable pressure controlling equipment, such as a float valve 21, to a 15 relatively low pressure heat absorbing zone shown in the illustrated embodiment as an evaporator 23, in which the liquid refrigerant is permitted to evaporate in order to absorb heat, the resulting vapors produced in evaporators 23 being returned to the suction or low pressure side of the refrigerant compressing means 17, preferably through a check valve 25.

The pumping means 17 comprises jet pumps 20 which are actuated by vapor under pressure preferably derived by the application of heat to a 25 suitable medium, which medium may comprise a portion of the refrigerating medium itself. The operation of a refrigerating system by means of jet pumps, as demonstrated in the aforesaid 30 application of William C. Grunow et al. for United States Letters Patent, is feasible providing the refrigerating medium has vapor pressure characteristics such that under normal temperature conditions the refrigerant may be evaporated and condensed within certain pressure differentials commercially maintainable. Such a 35 medium is trichloro-trifluoro-ethane $C_2F_3Cl_3$, commonly known as "Carrene No. 3."

In a system of the character described a portion 40 of the condensed refrigerant may be drawn from the condenser and delivered in the boiler 13 and there evaporated to produce vapor under pressure for the actuation of the jet pumps, the liquid delivered in the boiler 13 being there 45 evaporated by the application of heat in any suitable or convenient manner, as by the burning of fuel under the boiler 13, the same being illustrated as a gas burner 27. If desired, the vapor may be thoroughly dried and slightly 50 superheated by passing the same through the coil 29 before delivering it to the jet pumps 20.

The system, of course, may be operated by utilizing a pump actuating medium in the refrigerating medium, providing some means is 55 provided for separating the pump actuating medium from the refrigerating medium after the same are liquefied in the condenser. Furthermore, it should be clearly understood that the present invention is not necessarily restricted to 60 a boiler feed device for use in refrigerating systems of the character mentioned. At the same time the feeding device of the present invention is particularly well suited for delivering liquid from the condenser, which is at relatively low 65 pressure compared with the pressure maintained in the boiler 13, into the boiler, although it will be apparent that the feeding device may be used to deliver any kind of boiler feeding liquid to the boiler.

70 The invention may have application in connection with a boiler of any suitable or preferred construction. As shown for purposes of illustration, the boiler comprises a shell having fire tubes 31 heated by the combustion of gas or other fuel, the burner for which is located as shown

at the lower end of the boiler, and the products of combustion, after passing through the tubes 31, are conducted through a flue 33 of suitable construction, in which flue the superheating coil 29 may be arranged. 5

The boiler feed device 11 comprises means forming a chamber 35 vented by means of a conduit 37 to the source of supply 15 of the boiler feed medium, said conduit preferably connecting with the source above the liquid level therein, although the chamber 35 may, of course, be vented to atmosphere in the event that loss of the medium is of no consequence. Where, however, a valuable medium is used to feed the boiler, it is desirable to vent the chamber 35 to 10 the supply source. 15

The chamber 35 is also connected as by means of a conduit 39 with the boiler 13 so that the boiler pressure may be applied in the chamber 35 through said conduit 39. A valve 41 is arranged 20 in the conduit 39 to open inwardly toward the chamber 35 and a valve 43 likewise is arranged in the conduit 37 to open inwardly toward the chamber 35. These valves 41 and 43 are mechanically connected so that when one is closed 25 the other is open, and vice versa. The conduits 37 and 39 likewise open into the chamber in the upper portions thereof. The chamber 35 also is connected respectively by conduits 45 and 47 with the boiler 13 and with the source of supply, 30 there being a check valve 49 opening toward the boiler in the conduit 45 and a check valve 51 opening toward the chamber 35 in the conduit 47 so that liquid from the reservoir may be delivered into the chamber 35 through the valve 51, while 35 preventing back-flow of liquid through the conduit to the source 15 through the conduit 47. The check valve 49 likewise prevents flow of liquid from the boiler through the conduit 45 into the 40 chamber 35.

An expandible thermo-responsive element 53 is arranged in the chamber 35 in heat exchange relationship with respect to any liquid or gas that may be present therein. This thermo-responsive element 53 preferably comprises an expandible 45 container comprising a diaphragm or bellows having closed ends. Within the expandible container is sealed an evaporable medium having a vaporizing temperature which at all pressures is slightly less than the vaporizing temperature of 50 the boiler feed medium, at corresponding pressures. Any suitable or convenient medium, having the stated characteristics, may of course be employed, but where the boiler feed medium comprises "Carrene No. 3" the evaporable medium 55 within the expandible member 53 may comprise methylene chloride CH_2Cl_2 , (also known as dichloromethane) and commonly called "Carrene No. 1".

One end of the thermo-responsive expandible 60 means 53 is anchored relative to a wall of the chamber 35, the opposite end being free to move under the influence of the expansion or contraction of the medium contained within said element. The movable end of the means 53 is connected 65 with one end of the shiftable element 57, the opposite end of which is operatively connected with the valves 41 and 43.

The means or element 53 is preferably mounted, 70 vertically within the chamber 35 and we prefer to enclose it within a baffle 59 comprising a surrounding cylindrical element excluding the same from contact with the liquid entering the chamber 35 through the conduit 47 until the entering liquid reaches the level of the upper end of the 75

baffle 59 so that the element 53 may not be initially subjected to the temperature of the incoming liquid and in order to delay the operation of said element until the desired quantity has entered the chamber.

5 The valve 51 will remain closed as long as the pressure within the chamber 35 is in excess of that at the source 15, as when the valve 41 is open and the valve 43 is closed. The valve 41 is initially opened by contraction of the element 53 under the influence of the relatively cool temperature of liquid delivered in the chamber from the source of supply 15. As the valve 41 opens the valve 43 closes, blocking the vent conduit 37 and closing the valve 51 due to the application of boiler pressure in the chamber 35 through the conduit 39 and valve 41. Application of boiler pressure in this fashion equalizes the pressure in the chamber 35 and the boiler 13, thus permitting any liquid present in the chamber to drain by gravity into the boiler 13 through the valve 49 and the conduit 45. As soon as the liquid has thus drained sufficiently to substantially uncover the element 53 the temperature of the vapors received from the boiler is applied to the element 53, which causes vaporization of the medium within said element. This, in turn, expands the member 53 sufficiently to close the valve 41 and open the valve 43, the area of the valve 41 being sufficiently small to permit the pressure generated by the vaporization of the medium in the element 53 to overcome the boiler pressure and close the valve 41 against such pressure.

Upon opening of the valve 43 the gaseous content of the chamber 35 is vented to atmosphere or to the condenser above the liquid level therein, thus relieving the pressure within the chamber and equalizing the pressure with that prevailing at the source of supply 15. This permits liquid 40 to drain from the source of supply through the conduit 47 into the chamber 35. As soon as the liquid reaches a level in the chamber 35 sufficient to cover the element 53 the relatively cooler liquid absorbs heat from the member 53 and causes condensation of the evaporable medium within said expandable element. Condensation of the medium is ensured since, as heretofore stated, the vaporization temperature of the medium in the element 53 is slightly lower than that of the boiler feed medium. Upon condensation, the element 53 is caused to contract, thus permitting the valve 49 to open under the influence of boiler pressure to thereby allow the liquid in the chamber 35 to drain through the conduit 45 into the boiler, in a repetition of the operating cycle 55 of the device.

As shown in Fig. 2, the chamber 35 comprises a dome-shaped casing or shell 61 secured to a head block 69 and formed at its lower end for the reception of the conduits 45 and 47. The head block 69 also has secured thereto a generally U-shaped depending strap or bracket 65, to the transverse arm of which is fastened as at 55 the element 53. The baffle 59 is also secured in any suitable manner to the transverse arm of the bracket 65. Into the head block 69 is threaded a sleeve 71 which carries an inner clamping sleeve 73. The lower end of the clamping sleeve 73 secures the upper end of an expandable diaphragm or bellows 75 to the bottom of the holding sleeve 71, which bellows encloses a stem 77 of the member 57 and presses upon or is secured to a shoulder formed at the lower end of said stem. This arrangement is for the 70 purpose of sealing the opening through which

the member 57 extends. This member 57 comprises the stem 77, the lower end of which is connected to the free end of the element 53, the upper end of which is provided with a bearing 79 for receiving the lower end of a rod 81 which is slidably guided in the sleeve 73. The upper end of the rod 81 carries an adjustable bearing element 83 in position underlying the lower end of a valve element or rod in which the valves 41 and 43 are formed, the valve 41 being arranged at the upper end of the element in position opposite means 87 forming a valve seat as well as a connection for the attachment of the conduit 39.

10 The seat-forming means 87 comprises a plug 15 threaded in the end of a cap casting 89 which, in turn, is bolted upon a block 91, the block 91 being secured upon the upper end of the block 69 and providing a cavity 93 for the reception of the sleeves 71 and 73. The block 91 also 20 receives a seat 95 for the valve 43, while the cap element 89 provides a cavity or chamber 97 for the reception of the valve element.

25 The chamber 35 is in communication with the valve chamber 97 through a conduit 99 which extends through the block 91, a conduit 101 which extends through the block 69, a pipe 105 which connects with the conduit 99 and with the interior of the chamber 97. The block 91 is formed as at 107 for connection with the conduit 37 in order to vent the cavity 93.

30 It will be seen that the valve element comprising the valves 41 and 43 is normally gravity-actuated to close the valve 43 and open the valve 41 in order to apply boiler pressure through the conduit 39 and the connection 87 in the chamber 97 and thence through the pipe 105, the conduit 99 and the conduit 101 to the chamber 35, thus establishing boiler pressure in the chamber 35 and permitting any liquid therein to drain 40 through the conduit 45 into the boiler. The vapors received from the boiler cause the member 53 to expand and raise the stems 77 and 81 upwardly to permit the bearing element 83 to engage the valve 85 and raise the same to close 45 the valve 41 and open the valve 43. At this time the chamber 35 is vented through the conduit 101, the conduit 99, the pipe 105, the chamber 97, the valve 43, the cavity 93 and the conduit 39 to equalize the pressure within the chamber 35 with that prevailing at the source 15 and thus permit liquid to drain from said source through the conduit 47 into the chamber 35.

50 The arrangement shown in Fig. 2 is neat, inexpensive, compact and efficient. However, various other arrangements may be utilized. For example, as shown in Figs. 3 and 4, the member 57 may comprise a lever tiltable on a bracket 109, one end of the lever being connected with the valves 41 and 43 and the other connected 55 with the free end of the element 53. As shown in Fig. 3, also, a guide sleeve 111 may be arranged within the bellows 53.

55 As shown in Fig. 4, the lever 57 may be arranged in the form of a bell crank in order to 60 permit the mounting of the expandible element 53 on the bottom of the chamber 35, as distinguished from the side wall mounting of the element 53 illustrated in Fig. 3.

65 The feeding device of the present invention 70 has the advantages of compactness, efficiency and silence in operation, and affords an efficient means for delivering a liquid to a boiler. The invention, of course, has general application, although it is particularly well adapted for use in 75

connection with refrigerating systems of the character heretofore mentioned, and when so applied makes feasible the provision of a commercially satisfactory refrigeration system of the 5 compression-expansion-condensation type for operation by gas or other fuel.

It is thought that the invention and numerous 10 of its attendant advantages will be understood from the foregoing description, and it is obvious that numerous changes may be made in the form, construction and arrangement of the several parts without departing from the spirit and scope of the invention or sacrificing any of its attendant advantages, the forms herein described 15 being preferred embodiments for the purpose of illustrating the invention.

The invention is hereby claimed as follows:

1. A boiler feed device comprising a chamber, means for recurrently supplying the chamber 20 with boiler feed fluid, and means cyclically operable in accordance with the temperatures of the boiler and the boiler feed fluid for adjusting the pressure in the chamber substantially to the pressure of the boiler at alternate times with respect 25 to the operation of said recurrent feed means.
2. A boiler feed device comprising a chamber, means for recurrently supplying the chamber with boiler feed fluid, temperature responsive means cyclically operable for adjusting the pres- 30 sure in the chamber substantially to the pressure of the boiler at alternate times with respect to the operation of said recurrent feed means, and means to supply the said fluid to the boiler at the said pressure.
3. A boiler feed device comprising a member 35 providing a source of boiler supply fluid, a boiler member, a chamber member intermediate of said source and said boiler, temperature responsive means for alternately adjusting the pressure in 40 the chamber to substantially the pressure of the boiler and substantially the pressure of the said source, and means for permitting flow of boiler feed fluid between said members at said adjusted pressures.
4. A boiler feed device comprising a boiler member operating at relatively high pressure, a feed member containing boiler supply fluid at relatively low pressure, an intermediate member, conduit means connecting said feed member and 50 said intermediate member, conduit means connecting said intermediate member and said boiler for conveying supply fluid therebetween, and temperature responsive means for alternately adjusting the pressure in said chamber to substan- 55 tially that of the source and substantially that of the boiler, respectively, said conduit means being operative to permit flow between the respective members at substantially the same pressures.
5. In combination, a chamber operating at relatively high pressure, a source of supply fluid at 60 relatively low pressure, means to supply fluid from said source to said relatively high pressure chamber comprising an equalizing chamber, temperature responsive means to adjust the pressure of said equalizing chamber alternately to substantially said relatively high and said relatively low pressures, and means to feed supply fluid to said equalizing chamber at said low pressure and to said other chamber at said high pressure.
6. In combination, a chamber operating at relatively high pressure and high temperature, a 65 source of supply fluid at relatively low pressure and low temperature, means to supply fluid from said source to said relatively high pressure chamber comprising an equalizing chamber, tempera- 70
- 75

ture responsive means to adjust the pressure of said equalizing chamber alternately to substantially said relatively high and said relatively low pressures, and means operable to feed supply fluid to said equalizing chamber at said low pressure and therefrom to said other chamber at said high pressure. 5

7. A relatively high pressure element, a relatively low pressure element, means to supply fluid from said low pressure to said high pressure element comprising an additional chamber element, temperature responsive means for alternatively adjusting the pressure in said additional chamber element to substantially either said high or said low pressures, and means connecting said elements for permitting flow of said supply fluid between the elements at substantially the same pressure. 10

8. A relatively high pressure element, a relatively low pressure element, means to supply fluid from said low pressure to said high pressure element comprising an additional chamber element, temperature responsive means for alternatively adjusting the pressure in said additional chamber element to substantially either said high or said low pressure, and means connecting said elements for permitting uni-directional flow of said supply fluid between the elements at substantially the same pressure. 20

9. A relatively high pressure element, a relatively low pressure element, means to supply fluid from said low pressure to said high pressure element comprising an additional chamber element, temperature responsive means for alternatively adjusting the pressure in said additional chamber element to substantially either said high or said low pressures, conduit means for connecting said elements, and means associated with said conduit means for permitting uni-directional flow only of supply fluid from the low pressure element 40 to the said additional chamber under substantially equalized pressure and from said additional chamber to said high pressure element only under substantially equalized pressure whereby to cyclically feed said high pressure element. 45

10. A relatively high pressure and high temperature element, a relatively low pressure and low temperature element, means to supply fluid from said low pressure to said high pressure element comprising a chamber element, means connecting said elements for alternatively changing the fluid pressure in the chamber element to that of the said low and high pressure elements to equalize the pressures therein, means connecting said elements for permitting flow of said supply fluid between the elements at substantially the same pressure, and temperature responsive means located in the path of said admitted fluid and actuated by the temperature thereof to control said admission. 50

11. In combination, a relatively high pressure element and a relatively low pressure element, means to supply fluid from said low pressure to said high pressure element comprising a chamber element, conduit means to convey fluid from said relatively low pressure element to said chamber element when said last named element is at the said low pressure, means to convey fluid from said chamber element to the high pressure element when the said chamber element is at the 65 said high pressure, and means responsive to the temperature of the admitted fluid to alternately apply said predetermined pressures in said chamber element. 70

12. In combination, a relatively high pressure 75

element and a relatively low pressure element, means to supply fluid from said low pressure to said high pressure element comprising a chamber element, pressure equalizing conduits between 5 said chamber element and said other elements, valve means for opening and closing each conduit, fluid control conduit means between said chamber and said other elements, the fluid control conduits having associated therewith uni-directional flow control means to permit flow only 10 from the fluid source to the said chamber element and from said chamber element to the relatively high pressure element whereby to permit said uni-directional flow of supply fluid between 15 said elements when the said respective valve control means is open, and a temperature responsive sylphon arranged in the said chamber element and operatively connected to the said valve means to alternately change the pressure 20 of said chamber to correspond to that of the high and low pressure elements, said sylphon being actuated according to the temperature of the fluid admitted.

13. In combination, a relatively high pressure element and a relatively low pressure element, means to supply fluid from said low pressure to said high pressure element comprising a chamber element, pressure equalizing conduits between 25 said chamber element and said other elements, valve means for opening and closing each conduit, fluid control conduit means between said chamber and said other elements, the fluid control conduits having associated therewith uni-directional flow control means to permit flow only 30 from the fluid source to the said chamber element and from said chamber element to the relatively high pressure element whereby to permit said uni-directional flow of supply fluid between said elements when the said respective valve control 35 means is open, a temperature responsive sylphon arranged in the said chamber element and operatively connected to the said valve means to alternately change the pressure of said chamber to correspond to that of the high and low pressure element, said sylphon being operable to 40 actuate said valves to admit pressure from said high pressure element when contacted by fluid from said low pressure element and being reversely operable under the influence of fluid from the high pressure element, and baffle means arranged to delay action of the sylphon.

14. In a refrigerating system having a compressor, said compressor being actuatable under the influence of high pressure fluid and a source of high pressure fluid, means for supplying make-up fluid to said high pressure source from the 5 system comprising a chamber, means for periodically supplying the chamber with boiler feed fluid, and temperature responsive means alternately operable in accordance with the temperature 10 of the high pressure source and the make-up fluid for adjusting the pressure in the chamber substantially to the pressure of the boiler.

15. In a refrigerating system having a jet type compressor for compressing refrigerant, a boiler for supplying fluid under pressure to actuate 15 said jets, means for supplying make-up fluid to said boiler from a relatively low pressure point in the system comprising a chamber intermediate of said low pressure point and said boiler, temperature responsive means for cyclically adjusting 20 the pressure in said chamber to substantially the pressure of said boiler and for alternately adjusting said pressure to the pressure of said relatively low pressure point in the system, and means for permitting the flow of boiler feed fluid 25 between said members at said adjusting pressures.

16. A boiler feed device comprising a chamber, means for supplying the chamber with boiler feed fluid, and temperature responsive means for adjusting the pressure in the chamber substantially 30 to the pressure of the boiler whereby to feed the fluid from said chamber to said boiler.

17. In a device for feeding fluid to a boiler from a source of feed fluid, a chamber and means responsive to the temperature of the boiler fluid 35 and to feed fluid from said source to said chamber and means responsive to the temperature of the feed fluid to feed said fluid from said chamber to said boiler.

18. In a device for feeding fluid to a boiler from a source of feed fluid, a chamber, and temperature responsive means alternately operable to feed fluid from said source to said chamber at the pressure of said source and to said boiler 45 from said chamber at the pressure of said boiler.
